UNITED STATES PATENT OFFICE.

CHARLES A. TATUM, OF NEW YORK, N. Y., ASSIGNOR TO WHITALL, TATUM & CO., OF SAME PLACE.

DESIGN FOR A STANDARD FOR TABLET-MACHINES.

SPECIFICATION forming part of Design No. 23,921, dated December 25, 1894.

Application filed November 28, 1894. Serial No. 530,275. Term of patent 14 years.

To all whom it may concern:

Be it known that I, CHARLES A. TATUM, a citizen of the United States, and a resident of the city, county, and State of New York, have invented and produced a new and original Design for Tablet-Machine Standards, of which the following is a full, clear, and exact description.

The leading feature of my design consists in a perforated tablet machine standard rising from a base and having projections thereon of essentially the configuration and representation shown in the accompanying drawing.

In the drawing, A is the standard proper which rises from a base B and is perforated near its upper extremity as at C.

a is a rounded projection located near the highest point of the standard.

b b are ridges on the face of the standard running longitudinally thereof.

c is a rounded perforated projection on the face of the standard and located below the ridges b b.

d d are projections on the standard located below the projection c.

e e are projections on the horizontal face of the projections d d, and f f are projections on the base.

What I claim is—

The design for a tablet machine standard, substantially as herein shown and described.

CHARLES A. TATUM.
